CLAIM

The ornamental design for a barking restraining device, as shown and described.

DESCRIPTION

FIG. 1 is a perspective view of a barking restraining device consisting of a remote controller and a receiver according to the present application;

FIG. 2 is a front, right, and top perspective view of a remote controller of the barking restraining device of FIG. 1;

FIG. 3 is a rear, left, and bottom perspective view thereof;

FIG. 4 is a front elevation view thereof;

FIG. 5 is a rear elevation view thereof;

FIG. 6 is a left side elevation view thereof;

FIG. 7 is a right side elevation view thereof;

FIG. 8 is a top plan view thereof;

FIG. 9 is a bottom plan view thereof;

FIG. 10 is a front, right, and top perspective view of a receiver of the barking restraining device of FIG. 1;

FIG. 11 is a rear, left, and bottom perspective view thereof;

FIG. 12 is a front elevation view thereof;

FIG. 13 is a rear elevation view thereof;

FIG. 14 is a left side elevation view thereof;

FIG. 15 is a right side elevation view thereof;

FIG. 16 is a top plan view thereof; and,

FIG. 17 is a bottom plan view thereof.

FIGS. 2-17 are shown separately for ease and clarity of illustration.

The broken lines in the drawings depict portions of the barking restraining device that form no part of the claimed design.
